CLAIM

The ornamental design for a door for oven range as shown and described.

DESCRIPTION

The patent or application file contains at least one drawing executed in color. Copies of this patent or patent application publication with color drawing(s) will be provided by the Office upon request and payment of the necessary fee.

1. Door for oven range

1.1 : Perspective

1.2 : Front

1.3 : Back

1.4 : Left

1.5 : Top

1.6 : Bottom

The omitted right view is a mirror image of the left view. The broken lines shown in reproductions 1.1 to 1.6 depict portions of the door for oven range that form no part of the claimed design.

1 Claim, 7 Drawing Sheets
